WALTER B. CROAN, OF CHICAGO, ILLINOIS.

HEAT INTERCHANGER.

Application filed April 21, 1924. Serial No. 707,971.

The main object of this invention is to produce an improved heat interchanger for universal use and of economical construction; to provide a radiator capable of operating on direct steam pressures obtained from power boilers, thus permitting the use of direct high temperature steam for indirect radiation and at the same time to provide a highly efficient and reliable heat interchanging device adapted for use in vacuum, hot water, low pressure steam, and other systems; to provide an improved radiator which is applicable for both direct and indirect systems.

15 Radiators placed in a room are termed direct radiators. In such radiators the temperature is seldom above the boiling point of water, and the pressures correspond with the temperatures. Indirect radiation is used where ventilation as well as heating is required, and the range of temperature is controlled largely by the range of pressure available. One of the main uses of indirect radiators is in connection with the blower system of heating. Indirect radiation is also used where the temperature of the air to be delivered by the radiator, as used in drying systems, ranges from 200 to 400 degrees Fahrenheit.

20 The heat transmission of a direct radiator is usually expressed in terms of a transmission constant, or the B. t. u. emitted per hour per square foot of external surface per degree in temperature between the heating medium and the surrounding air. For direct radiation the value of this constant varies from substantially 1.5 for cast iron radiators and goes to approximately 2.18 for wall type radiators and for pipe coils.

25 The main object of this invention is the production of a light cast iron radiator, which is especially adapted for indirect radiation and where the required delivery temperature of the air necessitates the use of steam under pressures from 50 to 125 pounds gage. Such indirect radiators are operated in a duct with the blower system, so that air rapidly passing such a radiator must be able to make a rapid interchange of heat.

30 The principal and main points in the construction of such a radiator are: First, it must have the mechanical strength to stand the high pressures. Second, it must have a large radiating surface, such radiating surface so disposed as to promote the rapid transmission of heat through the iron and

from the steam or other heating medium to the air or other fluid passing the coils. The third and one of the most important items in the construction of a radiator for indirect radiation is that when placed in an enclosed passage it is an obstruction to the current of air. It becomes very necessary that such an obstruction should not disturb the even distribution of velocity throughout the conduit, and mechanically should form the least possible obstruction to the passage of air.

35 The even distribution of pressure and velocity in a conduit is through this invention accomplished by designing the radiator with a very large number of air or fluid passages which are symmetrically arranged over the entire surface, each individual passage being substantially a Venturi tube.

40 An important property of the Venturi tube form for the air passages is that it increases the pressure of the air on the heating surfaces as it passes through the radiator. The increased pressure of the air forces the air into more intimate contact with the surface of the tube so that the passage of air through the tube substantially wipes the exposed iron surface of the radiator, thus more effectively taking up the heat.

45 The obstruction to the flow of air is very slight because of the stream-line sectional form of the fins and steam conduits and the fact that these structures are placed edge-wise to the flow. The entire radiating surface is of Venturi tube form, and further, all of the metal comprising the radiating surfaces or fins is disposed in such a manner as to reinforce the steam carrying conduit giving a high factor of safety.

50 Referring to the drawings,—

55 Figure 1 is a front elevation partly in section of a specific form of radiator embodying this invention.

60 Fig. 2 is an end view partly in section along the line 2—2 of Fig. 1.

65 Fig. 3 is a section view along the line 3—3 of Fig. 1.

70 Fig. 4 is a section view along the line 4—4 of Fig. 1.

75 In the form shown, the radiator comprises headers 1 and steam conduits 2, and reinforcing fins 3. The ends of the headers are provided with tapped openings 4. The preferred sectional form of the steam conduits 5 is shown as in Figs. 3 and 4. The transverse sectional form of the fins is shown in Fig. 2.

The arrangement and shapes of the fin and the conduit surfaces forms between them a multiplicity of Venturi tubes.

The radiator is a single casting in which 5 the fins 3 act as reinforcement for the steam conduits 2.

This design is of special interest in foundry production processes, since it makes an ideal pattern to be drawn out of the sand and 10 provides a symmetrical arrangement of the cores of the steam passages. This design also provides for the maximum strength, due in part to the fact that the metal is so distributed that in the casting process, uniting 15 form cooling takes place throughout the casting thus preventing strains due to uneven shrinkage and crystallization. This construction also makes possible headers cast integral with the steam conduits and entirely 20 devoid of joints of any kind.

In installing this type of radiator, all that is necessary is to connect it with the inlet and outlet pipes.

It has an extraordinarily high heat transmission coefficient. Tests of the radiator when used for direct radiation show that its constant is above 2 and when used with high pressure steam for delivery of high temperature air for indirect heating purposes, the 30 contact is very much above that of pipe coils even when equipped with fins.

The form of the radiator is also advantageous, being smooth and even throughout and substantially rectangular in outline. 35 There is no special back or front or top or bottom. It works and drains properly in any position since the openings are symmetrically disposed at the four corners thereby preventing the formation of a trap in the 40 circulation system. When drained the amount of water left in the pockets in this radiator, independent of position, is so small that it is of no importance. When designed with closely spaced steam ducts and fins as 45 illustrated, the radiator becomes a reinforced grill or grating which can be installed floor flush and used to fill an aperture in the floor or in a walk.

In indirect heating systems where radiators are installed in a duct, it is often necessary to connect the radiators to a high pressure steam line, necessitating the use of pressure regulators and steam traps and a special return steam pipe line back to the source 55 of supply. Such construction is necessary because ordinary radiators are not capable of withstanding the steam pressures used for power purposes and their installation re-

quires, not only the extra expense of the installation of the regulators, but the cost of 60 maintenance and inherent losses in the regulators, cost of the traps and their installation, the cost of the special return pipe and pumps which are required to return the condensed steam. It also becomes necessary in 65 order to secure high temperatures with low pressure steam to stack the radiators which requires not only the expense of installing extra radiators, but the installation of such extra radiators in a duct means increased 70 air resistance and therefore increased force or blower capacity. This increases both the cost of installation and operating expense.

The herein described high pressure radiators, can be connected direct to the high pressure steam line whereby the radiators operate at a higher temperature, a smaller number of radiators will be required, the steam line will be of smaller capacity, and no extra return or traps or pumps will be required, since the condensed steam can return by gravity.

Although but one specific embodiment of this invention has been herein shown and described, it will be understood that numerous details of the construction shown may be altered or omitted without departing from the spirit of this invention as defined by the following claims.

I claim:

1. A steam radiator comprising a pair of separate spaced headers, a plurality of independent imperforate tubes of elongate cross section arranged with the major axes of the elongate sections extending from front to back of the radiator, said tubes being connected at their ends to said headers so as to provide communication between said headers, and a plurality of solid radiating fins integral with and disposed transversely to said tubes.

2. A steam radiator comprising a pair of separate spaced headers, a plurality of independent imperforate tubes of diamond shaped cross section arranged with the major axes of the diamond shaped sections extending from front to back of the radiator, said tubes being connected at their ends to said headers so as to provide communication between said headers, and a plurality of solid radiating fins of diamond shaped cross section integral with and disposed transversely to said tubes.

Signed at Chicago this 18th day of April 1924.

WALTER B. CROAN.
